GAME APPARATUS

Hollis L. Roberts, Manchester, Mass.

Application May 17, 1933, Serial No. 671,468

2 Claims. (Cl. 273—38)

This invention relates to that type of game apparatus which includes a portable bowling alley proportioned to rest on a table, and having a forward end formed to support bowling pins, 5 and a rear end from which balls may roll to the forward end, and a dirigible runway formed and arranged to receive a ball at a point above, and near the forward end of the alley to conduct a ball first away from the forward end toward 10 the rear end, and then reverse the direction of the ball, deliver it on the rear end of the alley, and cause its movement along the alley to the front end, the runway being dirigible by swinging it on a vertical axis to vary the path of the 15 ball.

The invention is embodied in certain improvements in the form and construction of the runway, the same being a bent tube characterized as hereinafter described, and in means for supporting the tube in such manner as to permit 20 dirigibility thereof.

Of the accompanying drawing forming a part of this specification,—

Figure 1 is a perspective view of the game apparatus embodying the invention.

Figure 2 is a top view of the same, the major portion of the tube being broken away.

Figure 3 is a fragmental edge view showing a portion of the alley, and the bridge hereinafter 30 described folded upon the alley.

Figure 4 is a section on line 4—4 of Figure 1.

Figure 5 is a view similar to Figure 2 illustrating a phase of the operation.

The same reference characters indicate the 35 same parts in all of the figures.

The alley is portable and proportioned to bear on a table or other support, its preferred length being about six feet. The ball track 12 of the alley has a forward end on which bowling pins 40 13 may be assembled in triangular formation, and a rear end from which a ball 14 may roll to the forward end.

In this instance the alley includes also a base 15 to which the ball track is attached, and marginal members 16 attached to and projecting below and above the base. Longitudinal gutters 17 extend beside the track and a transverse gutter 18 extends across the forward end of the track.

The apparatus is characterized as next described.

A dirigible ball guiding tube is mounted on the track. Said tube includes a ball delivering end portion 19 bearing on the head end of the track 12, a neck portion 20 curved upward from the 55 delivering portion 19, and extending forward to

ward the forward end of the track, and a ball-receiving end portion 21 longer than the delivering portion inclined upwardly from the neck portion and extending forward to a point above the central portion of the track.

The delivering portion 21 is pivotally connected with the rear end of the track 12 by means constituting a substantially vertical axis on which the tube is adapted to swing to vary the path of a ball emerging from the delivery portion 65 21, and rolling on the rack 12. Said means is embodied in this instance in a vertical socket 22 inserted in the rear end of track 12, and a pivot stud 23 adapted to turn in the socket, and provided with a curved head 24 which is soldered, or otherwise attached, to the under side 70 of the delivering portion.

With the alley is connected a bridge including a horizontal guide member 25 elevated above and extending crosswise of the alley, and movably 75 supporting the inclined tube portion 21. Said bridge preferably includes standards 26 pivoted at 27 to side portions of the alley, and engaged with the ends of the guide 25 said ends passing through orifices in the standards and having wing 80 nuts 28 seated on the standards.

The bridge includes also braces 29 pivoted at 30 to the standards, and having slots 31 in their free ends. Bolts 32 fixed to the side portions of the alley are adapted to extend through the slots 85 31, and are provided with clamping nuts 33 adapted to detachably secure the slotted ends of the braces to the alley. When the braces are detached from the alley the bridge may be folded as shown by Figure 3, the guide member 25 entering notches 34 in the alley sides. The pivot member 23 is withdrawable from the socket member 22, and the inclined portion 21 is separable from the guide member 25, so that the tube may be laid flat on the alley to complete the compact 95 folding of the apparatus.

The direction of the progressive movement of a ball rolling in the tube is reversed by the passage of the ball through the neck portion 20, and the base of the neck portion acts to indefinitely alter 100 the direction of the torque of the ball so that the path of the ball emerging from the tube is more or less uncertain. Long continued use of the apparatus demonstrates the fact that when a player has imparted a given adjustment to the 105 tube and sends balls successively through the tube without varying its adjustment, the balls are liable to roll in different paths along the track as indicated by Figure 5, in which the diverging dotted lines 37, 38 and 39 indicate the paths of 110

three balls successively sent through the tube while the latter is at a predetermined adjustment.

The divergence of said paths is due to changes 5 in the direction of the torque of the balls when they are passing through the neck portion of the tube. Said neck portion therefore constitutes a hazard in that a player cannot rely on a given adjustment of the tube to direct the ball against 10 an objective formed by a given pin, or pins.

I claim:

1. A portable game apparatus of the bowling alley type which includes a ball track having a forward end formed to support bowling pins, and 15 a rear end from which a ball may roll to the forward end, the apparatus being characterized first by a dirigible ball-guiding tube including a ball-delivering end portion bearing on the head end of the track, a neck portion curved upward from 20 the delivering portion and extending forward toward the forward end of the track, and a ball-receiving portion longer than the delivering portion, inclined upwardly from the neck portion and extending forward to a point above the central portion of the track, the ball-delivering portion being pivotally connected with the rear end 25 of the track by means constituting a substantially vertical axis on which the tube is adapted to swing

horizontally to vary the path of a ball emerging from the delivering portion, and secondly a horizontal guide member elevated above and extending crosswise of the track, and movably supporting the inclined portion of the tube, the tube bore having a diameter greater than that of the balls employed, so that a ball may roll freely from end to end of the tube, the curved neck portion acting to reverse the direction of the progressive movement of the ball, and to indefinitely alter the direction of its torque so that the path of a ball emerging from the tube is uncertain.

2. A game apparatus as specified by claim 1, said guide member being supported by standards pivoted to side portions of the alley and engaged with the ends of the guide, and braces detachably connected with the alley and pivoted to the standards, said guide member standards and braces constituting a bridge which is foldable against the alley when the braces are detached therefrom, the pivot member of the tube being withdrawable from the socket member in the track, and the inclined portion of the tube being separable from the guide member, so that the tube may be laid upon the alley to complete the folding of the apparatus.
